JAMES FREDERICK TRAVIS, OF NEW YORK, N. Y.

Design No. 3,235, dated November 10, 1868.

DESIGN FOR THE BRANCHES OF A GASOLIER.

The Schedule referred to in these Letters Patent and making part of the same.

To all whom it may concern:

Be it known that I, JAMES FREDERICK TRAVIS, of the city, county, and State of New York, have originated a new Design for the Branches of Gasoliers, of which the following is a full, clear, and exact description, reference being had to the accompanying photograph, forming a part of this specification.

The new and ornamental design for the branches of gasoliers and chandeliers, shown in the accompanying photographic view, consists of a branch, A, of square or quadrilateral formation in its transverse section, and recessed upon its front and lateral surfaces with ornamented panelling, in the manner as shown in the view. The said branch A has upon its upper extremity a square head, a, upon which is supported, by means of a neck, b, an upwardly-extending, pointed, or tapering ornament, c, of bayonet-like formation, having its outer or front surface recessed with ornamented panelling, as shown, and is supported upon the neck b by means of curved braces, d d. The said branch A extends from the head a in a downward and outward direction, and at a point thereon, as at o, there is attached upon the front surface thereof an ornament, m, of a character of formation as shown in the view. At a point further down thereon, as at e, the rear portion of the said branch recedes in a horizontal direction, so as to form a rearward continuation, f, of the branch A, having its upper and lower surfaces of a curvilinear formation, as shown. Immediately below this rearward continua-

tion, f, is a scroll-like ornament, i, extending from the rear extremity of said continuation, f, and terminating by a downward and an upward scroll, as represented in the view.

At the lower extremity of the branch A is an oblong formation, g, of square form in its transverse section, and attached vertically to the said lower portion of the branch A, as represented.

From the opposite side of the said formation, g, and in an upward and outward direction, there starts an extension or continuation, h, of the branch A. Said extension, h, is of a square formation in its transverse section, and is recessed upon its surfaces with ornamented panelling in the manner as shown.

Upon the outer extremity of the said extension, h, is an ornamented enlargement and termination, k, of the said branch A, perpendicularly arranged thereon, and is of a formation as represented in the accompanying photograph, the entire design embracing that portion bounded by red lines.

What I claim as my invention, and desire to have secured by Letters Patent, is—

The design for the branch of a gasolier, substantially as herein shown and described.

JAMES F. TRAVIS.
